METHOD OF OPERATING A HIGH SPEED SHELL FORGING PRESS

Philo H. Danly, Hinsdale, and Vasil Georgeff, La Grange Park, Ill., assignors to Danly Machine Specialties, Inc., Chicago, Ill., a corporation of Illinois

Filed Aug. 10, 1951, Ser. No. 241,272

1 Claim. (Cl. 205—8)

Our invention relates to a high speed shell forging press and more particularly to a press for forming elongated hollow articles such as cartridge cases and the like by a drawing operation.

Cartridge cases are formed by successive drawing operations. A flat blank is first cupped. The cup is then successively elongated in the plurality of drawing operations each of which elongates the shell until the final article is produced. In a typical case for a three-inch fifty-caliber cartridge case a flat plate is cupped in a press which requires a sixteen-inch stroke. The first draw requires a twenty-inch stroke. The second draw requires a twenty-five-inch stroke. The third draw requires a thirty-seven-inch stroke, and the final draw requires a fifty-two-inch stroke. It is known to the art that there are intermediate annealing operations between the draws. It will be appreciated that to provide a two hundred and fifty-ton press, for example, with a fifty-two-inch stroke, excessively large gearing will be required and that inasmuch as there is a critical drawing speed the punch is limited in its velocity of travel such that not more than about four strokes per minute can be employed. The large stroke is necessitated by the requirement that the punch enter the elongated shell of the workpiece produced by the previous draw to move to the position to begin the drawing operation. A press with a fifty-two-inch stroke will be a large and cumbersome machine which is expensive to build. These considerations make it substantially unfeasible to draw cartridge cases and the like by mechanical reducing or drawing presses known to the art and have made it necessary to use hydraulic presses. Hydraulic presses, on the other hand, are comparatively slow in their operation since the speed of the ram under the influence of hydraulic fluid pressure must necessarily be slow to obtain the mechanical advantage required. It will be seen, therefore, that no feasible method is known to the art for the rapid drawing of cartridge cases and the like.

One object of our invention is to provide a mechanical drawing press capable of comparatively rapid operation of about ten strokes per minute or more.

Another object of our invention is to provide a mechanical drawing press which is inexpensive in construction and of remarkably small size in view of the large stroke through which it is capable of acting.

A further object of our invention is to provide a mechanical drawing press for forming cartridge cases in which the drawing starts at a comparatively low speed and maintains a drawing speed less than the critical speed throughout the entire stroke.

Other and further objects of our invention will appear from the following description.

In general, our invention contemplates the provision of a main slide adapted to be reciprocated with simple harmonic motion through a driving train energized from a first prime mover. The main slide carries an auxiliary slide and a second prime mover adapted to drive a driving train of gears in predetermined phase relation with

the main slide. The punch for the drawing operation is carried by the auxiliary slide. The arrangement is such that the auxiliary slide will drive the punch downwardly and dwell. This dwell is achieved by the disengagement of the auxiliary slide clutch. As soon as the auxiliary slide stops its downward motion the main slide will commence its motion carrying downwardly the auxiliary slide and the punch along with the main slide. After the draw has been performed the auxiliary slide is again engaged with its drive train so that the punch will move upwardly at a high rate of speed due to the composite motion imparted to it both by the auxiliary slide and the main slide.

In the accompanying drawings which form part of the instant specification and which are to be read in conjunction therewith and in which like reference numerals are used to indicate like parts in the various views:

Figure 1 is a perspective view of a high speed shell forging press showing one embodiment of our invention.

Figure 2 is a sectional elevation drawn on an enlarged scale viewed generally along the plane 2—2 of Figure 1.

Figure 3 is a sectional view taken along the line 3—3 of Figure 2.

Figure 4 is a sectional view drawn on an enlarged scale taken along the line 4—4 of Figure 2.

Figure 5 is a phase diagram showing the phase relationships and amplitudes of motion of the various parts of our press in comparison with a press having a length of stroke equal to the stroke of both slides.

Figure 6 is a view showing the position of the punch, the workpiece and the stationary die before the commencement of the draw and showing the elongation achieved during the draw in the phase diagram of Figure 5.

Figure 7 is a motion diagram showing the motion of the main slide and auxiliary slide of our press for the second draw corresponding to the phase diagram shown in Figure 5.

More particularly referring now to the drawings, a press frame 10 may be of any suitable construction and supports a bed 12 on which the stationary die is supported. The movable die is carried by the auxiliary slide 14 which is mounted for reciprocation within the main slide 16 which is mounted for reciprocation within the frame 10. Suitable gibs 18 are carried by the frame for guiding the main slide and suitable gibs 20 are carried by the main slide for guiding the auxiliary slide 14. The guiding arrangement can best be seen by reference to Figure 4.

A prime mover such as an electric motor 22 is carried by the frame 10 and adapted to drive a main flywheel 24 through V-belts 26. A clutch in housing 28 is adapted to drivingly engage the flywheel 24 with the main drive shaft 30 of the main slide driving train. The drive shaft 30 is normally immobilized by a brake within housing 32. The arrangement is such that when it is desired to drive the main slide a control known to the art is energized to disengage the brake and engage the clutch to the flywheel. The press control is governed by a timing cam, not shown since it is well known to the art.

Whenever the clutch is engaged and shaft 30 driven, the pinions 34, which are secured to shaft 30 for rotation therewith, will drive gears 36 meshing therewith. Gears 36 are secured to shafts 38 supported in any suitable manner by the press frame. Shafts 38 carry secured thereto pinions 40 which engage crank gears 42 secured to crankshafts 44 mounted for rotation on frame 10. Each crankshaft is formed with a crankpin 46 around which is positioned a pitman 48. The lower end of each pitman 48 is pivotally secured to the main slide 16 by means of a pin 50. The arrangement is such that

the rotation of the cranks will reciprocate the main slide 16 with simple harmonic motion.

Secured to the main slide and supported thereby in any suitable manner we provide a second prime mover such as an electric motor 52 which continually drives a flywheel 54 through V-belts 56. A clutch is positioned within housing 53. This clutch is adapted to engage the flywheel with the shaft 58 supported for rotation upon the main slide in any suitable manner. A brake housing 60 is carried by the main slide and is adapted when the brake therein is engaged to immobilize the shaft 58. The arrangement is similar to the main driving arrangement and is well known in the art. It is such that when the clutch is engaged the brake is released so that the flywheel driven by the motor 52 will rotate the shaft 58. A worm 62 is secured to the shaft 58 for rotation therewith and engages a worm gear 64 formed with a crank 66 having a crankpin 68. A bell crank 74 is pivotally mounted upon a shaft 70 carried by the main slide. One arm 72 of the bell crank is connected by pin 76 through link 78 to the crankpin 68. The other arm 80 of the bell crank is connected to a link 82 by a pin 84. The other end of link 82 is connected by pin 84' to the auxiliary slide 14. The weight of the main slide and associated parts is counterbalanced by a pair of air cylinders 86 carried by the frame 10.

As can be seen by reference to Figure 1, the workpieces are fed to working position by a rotary feed plate 90 actuated through an arm 92. The feed forms no part of the instant specification and is therefore not described in detail.

Referring now to Figure 6, the punch 100 is carried by the auxiliary slide. The workpiece 102 is carried by the dial feed plate 90 in a guide bushing 104. The die 106 is carried by a back-up plate 108. A retaining plate 110 retains the die 106. A stripper plate 112 is provided. For the second draw the auxiliary slide will move through a distance of ten inches and the main slide will move through a distance of fifteen inches. For the third draw the auxiliary slide will move through a distance of seventeen inches and the main slide will move through a distance of twenty inches. For the final draw the auxiliary slide will move through a distance of twenty-four inches and the main slide will move through a distance of twenty-eight inches.

Referring now to Figure 5, which shows a graphic comparison between a complete 360° cycle of a conventional mechanical press, represented by the outer circle, and a complete cycle according to a press of the instant invention, as represented by the two inner circles, each circle represents the angular position of the crank at any designated point of the stroke. It will be readily seen in Figure 5 that the drawing portion of the downstroke of a conventional mechanical press starts at about midstroke when the punch has reached its maximum speed. This is necessarily so since in any reciprocating slide the maximum linear speed is reached at midstroke, assuming a constant speed of crank rotation. It will be further apparent, as can more readily be appreciated by reference to Figure 7, that in the instant invention the inherent disadvantage of the conventional mechanical press is eliminated since the draw actually starts at zero speed, that is, at the top of its stroke. The upper small circle A represents the rotation of the crankpin 68 of the auxiliary slide. The lower circle M represents the rotation of the crankpin 46. For the second draw the diameter of the circle A will be ten inches and the diameter of the circle M will be fifteen inches. For the final draw the diameter of the circle A would be twenty-four inches and the diameter of the circle M would be twenty-eight inches. It will be seen that the sum of the diameters of the circles A and M, that is, the strokes of the auxiliary slide and the main slide, will determine the over-all stroke of our press. After the dial feed has moved the workpiece 102 with its open end upwardly

into position under the punch 100 the clutch for the auxiliary slide is engaged while its brake is released. The auxiliary slide will then travel downwardly entering the punch into the workpiece 102. While this takes place the main slide rests at its top dead center, as can readily be seen by reference to Figure 7. At this point the auxiliary slide clutch is disengaged and the main slide clutch is engaged. The main slide then moves downwardly carrying with it the auxiliary slide and the punch and performs the drawing operation. It will be noted that the motor for the auxiliary slide is comparatively small and light as no function other than a positioning one is performed during the entering portion of the stroke. By reference to Figure 3 it will be seen that links 80 and 82 are extremely stout and at their bottom dead center form a straight angle. The entire thrust of the punch is transmitted from link 82 to link 80 to the stout pin 70 which is carried by the main slide. Link 78 forms a straight angle with link 66 and is maintained in this position through the worm wheel 64 and the worm 62, the shaft 58 which carries the worm 62 being immobilized by the brake 60. When the main slide moves downwardly it will draw with the punch being locked at its bottommost position in the manner just described. After the draw an overtravel is provided to push the shell formed by the draw through the die. It will be seen by reference to Figure 6 that the stripper plates 112 are immediately below the back-up plate of the die. As the shell is pushed through the die the stripper plates yield, as is well known to the art, and latch the finished shell in the lowermost position while the punch is being pulled out of the shell and die during the stripping operation. As soon as the stripping operation has been completed and the punch is free of the shell at about 240° of motion of the main slide the main slide starts returning. Slightly before this at about 230° of motion of the main slide the auxiliary clutch has been engaged so that both the main slide and the auxiliary slide move upwardly giving a composite upward motion as shown in Figure 7. At about 270° of motion of the main slide the dial feed will commence to feed the next workpiece and the cycle will repeat.

By reason of the rapid return due to the composite motion of the auxiliary slide and the main slide and the comparatively rapid downward motion of the auxiliary slide the speed of operation of the entire press can be greatly increased. From the normal four strokes per minute, which is the maximum possible with a single slide of conventional construction, we are enabled to increase the number of strokes to ten or more. By reference to Figure 7 it will be seen that the draw starts at a comparatively low speed and a safe drawing speed is not exceeded due to our combination. The composite curve of motion as shown in Figure 7 of the punch will be seen to comprise first a rapid motion caused by the auxiliary slide alone, after which the auxiliary slide dwells, then a motion due to the motion of the main slide alone and then a composite motion due to increments in an upward direction contributed by both the motion of the auxiliary slide and the main slide.

It will be seen that we have accomplished the objects of our invention. We have provided a mechanical drawing press capable of comparatively rapid operation of about ten strokes per minute or more which is inexpensive in construction and of remarkably small size for the large stroke through which it is capable of acting. We have provided a mechanical drawing press in which the drawing starts at a comparatively low speed and maintains a drawing speed less than the critical speed throughout the entire stroke.

It will be understood that certain features and sub-combinations are of utility and may be employed without reference to other features and subcombinations. This is contemplated by and is within the scope of our claims. It is further obvious that various changes may be made

in details within the scope of our claims without departing from the spirit of our invention. It is therefore to be understood that our invention is not to be limited to the specific details shown and described.

Having thus described our invention, what we claim is:

A method of drawing metal in a power press having a main slide and an auxiliary slide mounted on said main slide including the steps of placing a blank in the power press, extending the auxiliary slide to its bottom dead center position from an upper position, locking the auxiliary slide in its extended position, then reciprocating

the main slide and its carried auxiliary slide with simple harmonic motion through a working stroke and a return stroke and returning the auxiliary slide to its upper position during said return stroke.
